FURNITURE SCARF OR SIMILAR ARTICLE

Leo Fish, Forest Hills, N. Y., assignor to F. F. F. Textiles, Inc., New York, N. Y., a corporation of New York

Application June 1, 1950, Serial No. 10,298

Term of patent 3½ years

(Cl. D92—26)

To all whom it may concern:

Be it known that I, Leo Fish, a citizen of the United States, residing at Forest Hills, in the county of Queens and State of New York, have invented a new, original, and ornamental Design for a Furniture Scarf or Similar Article, of which the following is a specification, reference being had to the accompanying drawings, forming a part thereof.

Fig. 1 is a diagrammatic view of a furniture scarf or similar article showing my new design, with the design partially omitted for convenience in illustration.

Fig. 2 is a plan view of one end of the furniture scarf or similar article shown over a black background to bring out the details of the design.

I claim:

The ornamental design for a furniture scarf or similar article, substantially as shown and described.

LEO FISH.
